UNITED STATES PATENT OFFICE.

GEORGE S. BARKENTIN, OF NEW BRITAIN, CONNECTICUT, ASSIGNOR TO P.
& F. CORBIN, OF SAME PLACE.

DESIGN FOR A HINGE.

SPECIFICATION forming part of Design No. 20,082, dated August 12, 1890.

Application filed July 16, 1890. Serial No. 358,982. Term of patent 7 years.

To all whom it may concern:

Be it known that I, GEORGE S. BARKENTIN, a citizen of the United States, residing at New Britain, in the county of Hartford and State of Connecticut, have invented and produced a new and original Design for a Hinge, of which the following is a specification, reference being had to the accompanying drawing, forming part thereof, in which the only figure is a front elevation of a hinge showing my design.

The leading feature of my design consists in a sunken corded border between the plain border and panel.

15 The hinge-leaves A A are of the ordinary rectangular form, and are surrounded by a plain border a. Inside of said plain border is a groove or channel b, the ground or surface of which is ornamented by oblique beads

and depressions in imitation of a cord or rope, 20 forming what I term a "corded panel-border." The panel c inside the corded panel-border b is a plain surface corresponding with the outer border a. The tips B B are grooved circumferentially, the bottom of the groove having 25 the corded ornamentation d in harmony with the corded border b.

What I claim is—

The design for a hinge herein shown and described, the same comprising the rectangular leaves A A, the sunken corded panel-border b, with inclosed panel c and outer border a, as set forth.

GEORGE S. BARKENTIN.
